AUTO BODY REPAIR TOOL

Martin M. Ostrenga, Green Bay, Wis.

Application January 5, 1950, Serial No. 136,917

11 Claims. (Cl. 81—15)

1

This invention relates to improvements in auto body repair tools and particularly to anvils against which a deformed body surface is hammered in the re-shaping process.

The primary object of the invention is to provide an anvil which may be conveniently positioned against the irregularly contoured surfaces of an automobile body undergoing straightening, and which is provided with a handle and pivot means for universally rotating the anvil about the pivot, and means for yieldably biasing the anvil against the working surface with a pressure which approximates the yielding pressure available when an anvil is handheld.

A further object of the invention is to provide such a device with means for pre-adjusting the anvil to selected angular positions with relation to the handle in order to utilize the device at less accessible portions of a working surface.

Another object of the invention is to provide an anvil mounting whereby the desired features of a hand-held anvil are preserved even though the anvil is in extended position upon a handle, thereby permitting the anvil to be used at a spot heretofore considered inaccessible to the repair man.

Other objects will be apparent to those skilled in the art upon examination of the following disclosure.

In the drawings:

Figure 1 is a view in perspective of my handheld anvil.

Figure 2 is a plan view of the anvil and handle attachment portion of the invention.

Figure 3 is a view in longitudinal vertical section, of the device shown in Figure 2.

Figure 4 is a view in side elevation of the device shown in Figure 2, but showing the anvil rotated to a position normal to that in Figure 2 and showing the spring biasing device withdrawn on the handle.

Fig. 5 is a plan view of my tool with the anvil rotated on its ball mounting to a fixed angular position.

An anvil 6, which may be of forged steel or of like material, is provided with a handle 7, pivotally secured to the anvil through shaft 8 by means of a ball and socket arrangement. The anvil 6 is provided with a dished recess 9 into which the ball 10 is seated and maintained therein by means of a clamp plate 11 arcuately cut away at 12 to partially frame the ball. Desired frictional pressure on the ball 10 is maintained by the set screw 13.

It is thus seen that the anvil 6 is adjustable

2

about the ball 10, which arrangement in view of the contours of the anvil will permit approximate conformation with almost any surface. Stability of the anvil in certain pre-selected positions may be insured by means of a locking or indexing device including outrigger arms 14 with depending fingers 15. The arms 14 extend laterally from the handle shaft 8. The depending fingers 15 may alternatively seat into the shallow anvil depressions 16 which are located to receive fingers 15 with respect to the ball 10.

The anvil is yieldably biased against the working surface by means of a stabilizer spring 20 which bears against the bead 21. This provides a continuous rod-like frame secured, as by welding, to bracket 11 in a plane in general conforming to the plane of the top or the bottom of the anvil. The bead is provided with spaced notches 22 into which the spring 20 will selectively seat and hold the anvil in the positions assumed by it when rotated about the ball 10 and when the positioning fingers 15 are engaged with the anvil depressions 16. Thus the spring 20 also acts as an indexing and locking means. The stabilizer spring 20 is adjustably slideable in channel 25 of slide 23 and may be fixed by means of a set screw 24, or the like. The slide 23 is reciprocable on the shaft 8 and may be firmly positioned therealong by means of a thumb screw 26. The stabilizing spring 20 may thus be retracted when it is desired to rotate the anvil to the position shown in Figure 4.

In operation, the repair man reaches in beneath the fender (for example) of an automobile, and by exerting a slight pressure on the handle, will automatically rotate the anvil into general conformati on with the working surface. The resilience of the stabilizing spring 20 and of the operator's arm will provide proper yielding resistance to the mallet blows delivered in the straightening process. The operator can progressively move the anvil along the work, and the anvil will automatically accommodate itself to the configuration thereof. Depending upon the shape of the work, the operator may pre-adjust the anvil to various selected angular positions with relation to the handle in order to utilize the device at remote portions of the working surface.

50 I claim:

1. In an auto body repair tool, an anvil, a handle universally pivotally connected to the anvil, an outrigger arm extending transversely of the handle and provided with a depending finger 55 at the extremity of the arm, said anvil being pro-

vided with surface depressions disposed at the same distance from the handle pivot as the said finger whereby the finger may be selectively engaged in the depressions to stabilize the anvil in a certain position, and resilient means acting between the handle and the anvil to bias the finger into a depression.

2. In an auto body repair tool, an anvil, a handle pivotally connected to the anvil, a slide adjustably reciprocable upon the handle, and a springing stabilizing member detachably connected to the slide and a bearing bead mounted on the anvil and against which the stabilizing member is normally tensioned.

3. The device of claim 2 wherein the bearing bead is provided with spaced notches into which the springing stabilizer will selectively seat as the anvil is rotated about the handle pivot.

4. In an auto body repair tool, an anvil, a handle pivotally connected to the anvil, positioning arms extending transversely of the handle, depending fingers at the extremities of said positioning arms, said anvil being provided with a plurality of depressions aligned to selectively receive said depending fingers in certain position of adjustment, a slide member reciprocably adjustable on the handle, a leaf spring stabilizer detachably connected to the slide and extended longitudinally with the handle to overlie the anvil, and a bearing bead provided with spaced notches mounted on the anvil to receive pressure of the spring stabilizer.

5. The device of claim 4 wherein the bearing bead notches and the depressions in the anvil are so spaced with respect to the spring stabilizer and positioning arms as to be respectively simultaneously engaged when the anvil is rotated about the handle pivot to a selected position.

6. In the device of claim 4, a pivoting arrangement comprising a ball integral with the handle, said anvil being provided with a socket-like recess, a clamp plate elevated above the anvil and apertured to receive the ball positioned between the anvil socket and the clamp plate, and screw means through the clamp plate for adjusting the frictional pressure on the ball.

7. In an auto body repair tool, an anvil, a handle pivotally connected to the anvil, a bearing bead on the anvil and a spring mounted on the handle and tensioned against the bearing bead whereby to provide yielding support for the anvil.

8. The device of claim 7 wherein the anvil and handle are provided with co-acting indexing means disposed at the opposite side of the pivot from the bearing bead whereby said spring biases the indexing means to co-action when the anvil is in indexed position respecting the handle.

9. An auto body repair tool comprising members including an anvil and a handle, a universally pivotal connection between the anvil and the handle, means for adjustably tightening said connection to restrict universal pivotal movement of said members, and independent detent means for locking the anvil against rotation in a given plane, said detent means including a resilient stabilizing element against which the anvil may be yieldably displaced.

10. The device of claim 9 in which the said element comprises a strap spring yieldable from the plane of its surface to permit anvil displacement toward the spring and inherently non-yielding in a transverse direction, the anvil having shoulders laterally engageable with the spring.

11. The device of claim 9 in which said pivotal connection comprises a ball and an adjustable clamp plate embracing the ball, one of said members having a plurality of detent seats disposed arcuately about said ball, said resilient stabilizing element comprising a spring mounted in the other of said members for selective engagement in said detent seats.
